ENGINE STARTING MECHANISM

Carl O. Nygren, Michigan City, Ind., assignor to
 Sullivan Machinery Company, a corporation of
 Massachusetts

Application July 11, 1932, Serial No. 621,925

23 Claims. (Cl. 123—179)

This invention relates to engine starting mechanism of the inertia type, and more particularly to improved manually operable starting mechanism for facilitating the starting of internal combustion engines.

An object of this invention is to provide a simple, efficient and reliable mechanism designed to eliminate direct hand cranking and electric starters, permitting, with a minimum of strenuous effort, the safe and certain starting of engines which could not readily be started by an ordinary manual cranking operation. In a preferred embodiment, the invention may comprise a drive or transmission including an element adapted to be connected in driving relation to the ordinary ring gear of an engine fly wheel; inertia means, such as a fly wheel, gearing, as for example, planetary or epicyclic gearing connected with the inertia means for storing energy in the latter and transmitting the stored energy for starting purposes as aforesaid; starting means for actuating the gearing and the fly wheel, and means for connecting the gearing with the starting element after the starting element has been brought into mesh with the ring gear, or the like. Preferably, protective devices guarding against back-fire, and devices for automatically disconnecting the primary driving element from the ring gear will be employed, while a drive through the ring gear may be regarded for many purposes as preferable. The invention from some of its aspects may be of more general application. Other objects will herein-after appear in the course of the following description and as more particularly pointed out in the appended claims.

In the accompanying drawings there are shown for purposes of illustration two embodiments which the invention may assume in practice.

40 In these drawings,—

Fig. 1 is a horizontal sectional view through the preferred illustrative embodiment of the invention.

45 Fig. 2 is a transverse vertical sectional view taken substantially on line 2—2 of Fig. 1.

Fig. 3 is a longitudinally extending vertical sectional view taken substantially on line 3—3 of Fig. 1.

50 Fig. 4 is a detail sectional view taken on line 4—4 of Fig. 2.

Fig. 5 is a transverse vertical sectional view through the other illustrative embodiment of the invention, the view being taken substantially on line 5—5 of Fig. 7.

55 Fig. 6 is a view partially in elevation and par-

tially in section at right angles to Fig. 5, the section being taken through the axis of the starting mechanism.

Fig. 7 is a plan view of the starting mechanism shown in Figs. 5 and 6.

Figs. 8 and 9 are transverse vertical sectional views taken substantially on the plane of the lines 8—8, 9—9 of Fig. 6.

The preferred form of the improved engine starter shown in Figs. 1 to 4 inclusive, as a whole 10 is designated 1 and the ring gear of the fly wheel 15 of an engine to be started is indicated in construction at 2. The starter is, as regards the gearing thereof, wholly enclosed within a plural-part casing 3 which is secured to the fly wheel 15 housing indicated in construction at 4 and which, with the latter, provides oil tight housings for all the mechanism, so that adequate lubrication of the gearing and protection of the operator from the gearing may be effected. While it will 20 be evident that motor actuation of the engine 25 starter may be resorted to, if desired, there is for simplicity herein shown only manual starting means for actuating the gearing and fly wheel. A hand crank 5 is connectible through a rolling 25 pin and cam connection 6 (herein in the form of a ratchet) with a cranking shaft 7 rotatably supported in bearings 8 in a detachable closure member 9 forming a part of the starter casing 3. The starter casing also comprises an in- 30 tegral flange 10 for attachment to the fly wheel housing and has formed therein parallel com- 35 municating chambers 11 and 12. The casing structure also includes a cylindrical gear housing 13 arranged within the chamber 12 and main- 35 tained in position by a detachable end plate 14 as shown in Fig. 1. In this instance the inner 40 end of the shaft 7 carries and rotates a bevel pin- 40 ion 15 which meshes with a bevel gear 16 rotat- 45 ing on a horizontal axis extending longitudinally 45 of the starter mechanism and parallel to the power shaft of the engine to be started and pref- 50 erably at right angles to the starting shaft 7. The hub of this bevel gear 16 is keyed to a weighted crank or arm 17 and the gear 16 and 55 crank 17 are journaled and, in a measure, sup- 55 ported by a large ball bearing 18 supported with- in the adjacent end wall of the cylindrical hous- 60 ing 13. The arm 17 provides a bearing 19 for a planetary spur pinion 20 which meshes with 65 elongated horizontal internal gear teeth 21 formed upon the interior of the cylindrical hous- 70 ing 13, these teeth extending from a point adja- 75 cent the outer side of a pinion 20 substantially 75 to the outer end of the cylindrical housing 13. 55

A spur gear 23 is arranged coaxially with the bevel gear 16 and is keyed to a shaft, hereinafter referred to, journaled at its ends within bearings supported within the starter casing. This shaft to which the gear 23 is keyed has keyed thereto a spur pinion 24 with which the pinion 20 meshes, and also a counter-balanced crank or arm 25, the latter carrying a bearing 26 for a planetary spur pinion 27. The pinion 27 also meshes with 5 the internal gear teeth 21 and likewise meshes with and drives a gear 28 coaxial with the gear 24 and which is rigidly secured to a counter-balanced crank or arm 29. This counter-balanced crank supports a bearing 30 for another 10 planetary spur gear 31 likewise meshing with the internal gear teeth 21. The pinion 31 engages a gear 32 coaxial with the gears 24 and 28 and secured to a counter-balanced crank or arm 33, and this crank 33 carries a bearing 34 for a 15 planetary spur gear 35 which, in its turn, meshes with the internal gear teeth 21 and also meshes with spur gear teeth 36 upon a sleeve 37 coaxial with the gears 24, 28 and 32. Supported on and keyed at 38 to this sleeve is a fly wheel 39, this 20 fly wheel being supported by the sleeve and the sleeve being rotatably supported within a large ball bearing 40 in turn supported within the detachable end plate 14 of the cylindrical gear housing 13. The shaft to which the gear 23 is 25 secured is numbered 41 and the bearing within which the outer end of this shaft is journaled is supported within the sleeve 37, as shown in Fig. 1, this bearing being indicated at 42; and this shaft also serves to center and support a number 30 of roller bearings which provide the journals for the several cranks heretofore referred to. The spur gear 23 meshes constantly with a gear 45, which is journaled on a roller bearing 46 in turn supported on a shaft 47 herein arranged within 35 the chamber 11 and also parallel to the axis of the ring gear 2, and this shaft is rotatably supported at its ends within bearings supported within the starter casing 3. The shaft 47 is connected by a pin and slot connection 49 at its end near the ring gear 2 and also by a pin and slot connection 40 45 50 55 60 65 70 75 50 near its opposite end respectively to a spur pinion 51 and a jaw clutch member 54. The pinion 51 is adapted to mesh with the ring gear 2 and may be moved along the shaft 47 while driven thereby, due to the pin and slot connection 49, into engagement with and out of engagement with the ring gear 2. The gear 45 carries jaw clutch teeth 52 which are engageable with jaw clutch teeth 53 formed on the clutch member 54. The face of each of the teeth 52 is of a small angle to a plane including the axis of the shaft 47, so as to permit, in the event of a backfire, the breaking of the driving connections between the inertia starter and the engine fly wheel. There is also provided a comparatively flat surface having a large slipping angle so as to effect a gradual and smooth release between the gear 45 and the clutch member 54 when the engine is started. The pinion 51 and the clutch member 54 are secured by the pins of the pin and slot connections 49 and 50 respectively to a longitudinally reciprocable shaft 56 slideable in a bore 57 formed centrally in the shaft 47. Arranged within the bore within the shaft 47 is a coiled spring 65 acting between a plug 66 threadedly secured within the end of the shaft 47 and the end of the slideable shaft 56 to maintain normally the shaft 56 in the position shown in Fig. 3. A pivoted operating lever 67 has a slot and pin connection 68 with a trunnion member rotatably sup-

ported on a ball bearing member 69 engaged between a shoulder 70 on the shaft 56 and a screw and washer connection 71 secured to the shaft. Obviously, on movement of the lever 67 in the proper direction the members 54 and 51 will be moved toward the left, the member 51 engaging with the ring gear 2 and the member 54 effecting engagement of the teeth 53 with cooperating teeth 52 on the gear 45.

In the form of the invention shown in Figs. 5 to 9 inclusive, the gearing is substantially the same as that described in the preferred form, the main difference residing in the location of the axis of the bevel gear 16 and its associated gearing which, in this form of the invention, is vertical and at right angles to the axis of the longitudinal shaft 47. In this form of the invention a hand crank 5a is connectible through a pin and slot connection 6a with a cranking shaft 7a rotatably supported in bearings 8a in a detachable closure member 9a forming a part of the starter casing 3. The starter casing, in this form of the invention, comprises a base portion 10a, an upper cylindrical portion 11a and a detachable top plate 12a. The inner end of the shaft 7a carries and rotates a bevel pinion 15a which meshes with a bevel gear 16a rotating on a vertical axis lying in the same plane with the axis of the shaft 7a and carrying at its upper end a crank or arm 17a. The gear 16a and crank 17a are journaled and, in a measure, supported by a large ball bearing 18a supported by the lower end of the casing member 11a. The crank or arm 17a provides a bearing 19a for a planetary spur gear 20a which meshes with elongated vertical internal gear teeth 21a formed upon the interior of the cylindrical portion 11a of the starter casing, these teeth extending from a point adjacent the lower end of the pinion 20a substantially to the upper end of the cylindrical portion 11a of the casing. Another bevel gear 23a is arranged coaxially with the bevel gear 16a and carries near its upper end a pinion 24a with which the pinion 20a meshes, and also a counter-balanced crank or arm 25a, the latter carrying a bearing 26a for a spur planet gear 27a. The pinion 27a also meshes with the teeth 21a and likewise meshes with and drives a spur gear 28a which is rigidly secured to a counter-balanced crank or arm 29a. This counter-balanced crank supports a bearing 30a for another spur planet gear 31a likewise meshing with the teeth 21a. The gear 31a engages a spur gear 32a secured to a crank 33a, and the crank 33a carries a bearing 34a for a spur planet gear 35a which, in its turn, meshes with the internal gear teeth 21a, and also meshes with spur gear teeth 36a upon a sleeve 37a. The sleeve 37a has keyed thereto at 38a at its upper end a fly wheel 39a and is journaled within a large ball bearing 40a, this ball bearing also supporting the fly wheel 40 against downward axial movement. A long bolt 41a rotatably mounted within the sleeve 37a through a bearing 42a at its lower end supports the pinion 23a, and also serves to center and support a number of ball bearings which provide the journals for the several crank arms heretofore referred to. The pinion 23a meshes constantly with a bevel gear 45a which is journaled in a bearing 46a with its axis parallel to the axis of the ring gear 2. A shaft 47a, also parallel to the axis of the ring gear, is rotatably supported within the gear 45a and is splined at 49a at its end near the ring gear, and also at 50a near its opposite end. A spur pinion 51a adapted to mesh with the ring gear 2 is splined to the shaft 47a, 75 80 85 90 95 100

and may be moved along the latter into engagement with and out of engagement with the ring gear. The gear 45^a carries teeth 52^a which are engageable with teeth 53^a on a clutch member 54^a which is slidably engaged with the splines 50^a. The faces of the teeth 52^a are at a small angle to a plane including the axis of the shaft 47^a, so as to permit, in the event of a back-fire, the breaking of the driving connections between the inertia starter and the engine fly wheel. In the present construction, as in the preferred form above described, there is also provided a comparatively flat surface having a large slipping angle so as to effect a gradual and smooth release between the member 45^a and the clutch 54^a when the engine is started. The pinion 51^a and the clutch member 54^a are connected by a lost-motion connection mechanism 55 which includes a longitudinally slideable shaft 56^a slideable in a bore 57^a formed in the housing member 10^a, a forward arm 58 carrying a split bearing 59 co-operating with a groove 60 in the pinion member 51^a, and an arm 62 having a sliding connection in a groove 63 formed in a sleeve 64 which carries the member 54^a. Within the sleeve 64 a spring 65^a, acting between the end of the shaft 47^a and a threaded plug 66^a, is provided normally to maintain the mechanism 55 in the position shown in Fig. 6. A pivoted operating lever 67^a has a slot and pin connection 68^a with a ball bearing member 69^a engaged between a shoulder 70^a on the sleeve 64 and a flange 71^a on the plug member 66^a. Obviously, on movement of the lever 67^a in the proper direction, the members 54^a and 51^a will be moved toward the left, the member 51^a engaging with the ring gear 2 and the member 54^a effecting engagement of the teeth 53^a with their drive surfaces 52^a.

From the description given, the mode of operations of both forms of the mechanism will be clearly apparent. In the preferred form of the mechanism shown in Figs. 1 to 4 inclusive, the mode of operation is as follows. When it is desired to start the engine, the crank 5 will be turned in the proper direction to cause the roller pin and cam connection 6 to effect driving relation between the crank and the starting shaft 7. The shaft 7 will then be rotated and will drive the pinion 15, and the latter will drive the pinion 16 and cause the crank arm 17 to rotate. This will cause the planet gear 20 to roll around in engagement with the internal gear teeth 21 and thereby drive the gear 24. The latter will drive the crank arm 25, and rotation of the arm 25 will cause the planet gear 27 to be rotated through its engagement with the internal gear teeth 21, thereby to rotate the gear 28 to effect rotation of the crank arm 29. Rotation of the crank arm 29 will cause orbital movement of the planet gear 30 and, by virtue of the mesh of the latter with the internal gear teeth 21, rotation of the gear 32. The gear 32 will rotate the crank arm 33 which will cause the planet gear 35 to be rotated on its axis as it rolls around in mesh with the internal gear teeth 21 and thereby there will be effected rotation of the sleeve 37 with corresponding rotation of the fly wheel 39 at a very high speed, due to the great multiplication effected through the gearing described. The gear 23 will also be rotated during rotation by the hand crank 5, but will not be connected in driving relation to the engine fly wheel. When the fly wheel 39 has been brought up to speed, hand cranking will be discontinued and the fly

wheel 39, through its momentum, will become the driving member and will transmit a very slow but powerful rotation to the initial element of the train of gearing described and cause the large spur gear 23 to drive the spur gear 45. Upon movement of the lever 67 to the left in Fig. 3, the pinion 51 will be brought into driving engagement with the ring gear 2 and the teeth 53 into engagement with the surfaces 52. The engine will therefore be cranked. As soon as the engine starts, the shaft 47 will tend to rotate faster than the pinion 45 and will effect automatically disengagement between the teeth 53 and the teeth 52 and force the system controlled by the shaft 56 to the right to interrupt drive between the inertia starter and the pinion 51. On release of the lever 67, the pinion 51 will be moved completely out of engagement with the ring gear 22 and the parts of the inertia starter may come to rest. 20

In the form of the invention shown in Figs. 5 to 9 inclusive, the mode of operation is substantially identical to that described above. In this form of the invention the hand crank 5^a, when it is desired to start the engine, will be slid along the starting shaft 7^a to effect driving relation of the pin and slot connection 6^a. The shaft 7^a will then be rotated and will drive the pinion 15^a, and the latter will drive the sleeve 16^a and cause the crank 17^a to rotate. Rotation of this crank effects rotation of the fly wheel 39^a through the pinion 20^a, gear 24^a, crank arm 25^a, gear 27^a, gear 28^a, crank 29^a, gear 31^a, gear 32^a, crank arm 33^a, gear 35^a and sleeve 37^a to which the fly wheel 39^a is fixed. The bevel gear 23^a will also be rotated during rotation by the hand crank 5^a, but will not be connected in driving relation to the engine fly wheel. When the fly wheel 39^a has been brought up to speed, hand cranking will be discontinued and the fly wheel 39^a, through its momentum, will transmit a very slow but powerful rotation in a cranking direction through the gearing above described and cause the gear 23^a to drive the bevel gear 45^a. Upon movement of the lever 67^a to the left in Fig. 7, the pinion 51^a will be brought into driving engagement with the ring gear 2 and the teeth 53^a into engagement with the surfaces 52^a. The engine will therefore be cranked and as soon as the engine starts the shaft 47^a will tend to rotate faster than the bevel gear 45^a and will effect automatically disengagement between the inertia starter and the pinion 51. Upon release of the lever 67^a the spur pinion 51^a is removed out of mesh with the ring gear, thereby disconnecting the starter mechanism 55 from the engine. 45

As a result of the invention, it will be noted that there is provided a very simple, rugged, well protected inertia starting mechanism particularly adapted for use with fly wheel starters. It will further be noted that there is provided an improved starter mechanism which is extremely compact, which may be mounted on the engine casing and which may be operated with facility, the provision of the improved gearing between the hand crank and the fly wheel enabling an extremely powerful energy source to be obtained. These and other uses and advantages of the improved starter mechanism will be clearly apparent to those skilled in the art. 65

While there are in this application specifically described two forms which the invention may assume in practice, it will be understood that these forms of the same are shown for purposes of illustration and that the invention may be modified 75

and embodied in various other forms without departing from its spirit or the scope of the appended claims.

What I claim as new and desire to secure by Letters Patent is:

- 5 1. In an engine starting apparatus of the type in which a ring gear or the like on the engine is engageable during the starting operation by a terminal gear of the starter and such engagement is thereafter interrupted, a gear member adapted 10 to mesh with and drive the engine gear, an inertia wheel, manually operable means including a reduction gear train comprising intermeshing reduction gearing for storing energy in said inertia 15 wheel, and means for manually shifting said gear member into meshing engagement with said engine gear while said inertia wheel is rotating and thereafter connecting said gear member for drive by said inertia wheel through said gear train.
- 20 2. In an engine starting apparatus of the type in which a ring gear or the like on the engine is engageable during the starting operation by a terminal gear of the starter and such engagement is thereafter interrupted, a gear member adapted 25 to mesh with and drive the engine gear, an inertia wheel, manually operable means including a reduction gear train comprising intermeshing reduction gearing for storing energy in said inertia 30 wheel, and operator controllable means including a connection automatically releasable when said engine is started for effecting engagement of said gear member with said engine ring gear while said inertia member is rotating and thereafter connecting said gear member for drive by said 35 inertia wheel through said gear train.
3. In an engine starting apparatus of the type in which a ring gear or the like on the engine is engageable during the starting operation by a terminal gear of the starter and such engagement is 40 thereafter interrupted, a terminal starting gear, a shaft parallel with the shaft of the engine to be started and supporting said terminal starting gear, said terminal starting gear being reciprocable along its said supporting shaft between 45 positions of engagement with and disengagement from the engine, manually operable inertia means for storing up energy, and means operable at will and including a clutch coaxial with said terminal starting gear supporting shaft for connecting said inertia means in driving relation 50 with said supporting shaft.
4. In an engine starting apparatus of the type in which a ring gear or the like on the engine is engageable during the starting operation by a 55 terminal gear of the starter and such engagement is thereafter interrupted, a terminal starting gear, a shaft parallel with the shaft of the engine to be started and supporting said terminal starting gear, said terminal starting gear being reciprocable along its said supporting shaft between 60 positions of engagement with and disengagement from the engine, inertia means for storing up energy including a driving shaft parallel with said first shaft, gearing for connecting said first shaft and said parallel driving shaft in 65 driving relation, and means operable at will and including a clutch coaxial with said first shaft for connecting said inertia means in driving relation with said first shaft.
- 70 5. In an engine starter, a flywheel, an engine starting member, reduction gearing, including a reaction gear coaxial with said flywheel, for transmitting torque from said flywheel to said engine starting member, releasable means for connecting

said gearing to said engine starting member, and gearing for transmitting energy to said flywheel through said first mentioned reduction gearing including a further gear meshing with said reaction gear, said last mentioned gear being outside 5 the train of torque transmission from said flywheel to said engine starting member.

6. An engine starter including, in combination, a plural stage speed changing mechanism including coaxial members arranged in train and of 10 which, when one is rotating at one speed, a second rotates at a different speed and a third at an intermediate speed, said second coaxial member arranged in the train of power transmission outside the train between the first and third, an 15 inertia member operatively connected with the first of said coaxial members and arranged to drive the same during starting of the engine, a driving device for imparting energy to said starter for storage in said inertia member operatively 20 connected with the second of said coaxial members to drive the latter, an engine starting member, and means distinct from said train of power transmission aforesaid for operatively connecting said engine starting member with the third of said 25 coaxial members.

7. In an engine starter, a casing, a shaft rotatable within said casing, an internal gear within said casing, an arm carried by said shaft and carrying a gear meshing with said internal gear, 30 gearing rotatable by said second mentioned gear, a flywheel rotatable by said gearing, a gear fixed to said shaft, a gear meshing therewith and also meshing with said internal gear, an arm carrying said third mentioned gear, means for manually 35 effecting rotation of said arm for effecting the storage of energy in said flywheel, and means including another gear also fixed to said shaft for transmitting a starting torque to an engine to be started. 40

8. In an engine starter, a casing, an internal gear therein, a flywheel, reduction gearing for rotating said flywheel including a gear, an arm driven thereby, a gear carried by said arm and meshing with said internal gear, a gear meshing 45 with said last mentioned gear, an arm driven by said last mentioned gear, a gear carried by said last mentioned arm and meshing with said internal gear, a gear driven by said last mentioned gear, an arm driven by said last mentioned gear, 50 a gear carried by said arm and meshing with said internal gear, a gear driven by said last mentioned gear, and connections between said last mentioned gear and said flywheel, and an engine starting member, said starting member being rotatable by said flywheel through a train including all of said gears except the second and third. 55

9. In an engine starter, a flywheel, a pair of coaxially arranged rotatably supported gears, manual driving means for one of said gears, an 60 engine driving gear operatively connected with the other of said gears, a stage of speed changing gearing between said coaxially arranged gears whereby they rotate constantly at angular rates bearing a predetermined ratio to each other, further speed changing gearing driven by the first separately mentioned one of said pair of coaxially arranged gears, and an inertia member operatively connected with said last mentioned speed changing gearing, said engine driving gear 65 being driven by said inertia member through a power transmission train including said further speed changing gearing but excluding said first mentioned stage of speed changing gearing. 70

10. In an engine starter, a pair of bevel gears, 75

means operatively connecting said gears whereby a predetermined difference in angular rate of rotation is maintained between them, engine starting gearing driven by one of said gears, driving means for the other of said gears, and inertia means driven by said last mentioned gear for storing energy and delivering the same to the second mentioned bevel gear having a power transmitting train connecting it with the latter 10 of which the means operatively connecting said bevel gears for rotation at different rates forms no part.

11. In an engine starter, inertia mechanism, a driving shaft, a gear driven by said inertia mechanism, a gear supported on said driving shaft and engaged by said last mentioned gear, an engine driving gear slidably mounted on said driving shaft, sliding clutch means between said first mentioned gear on said shaft and said shaft, 20 and means for sliding said sliding gear into driving position on said shaft and thereafter connecting said clutch means.

12. In an engine starter, inertia means, a terminal starting gear, a shaft on which said terminal gear is slidably mounted, intermeshing reduction gearing adapted to connect said inertia means with said shaft, a clutch for connecting said gearing to drive said shaft, actuating means for said clutch, and means actuated by the actuating means for said clutch for moving said terminal gear longitudinally of said shaft.

13. In an engine starting apparatus of the type in which a ring gear or the like on the engine is engageable during the starting operation by a terminal gear of the starter and such engagement is thereafter interrupted, a gear member adapted to mesh with and drive the engine gear, an inertia wheel, manually operable means including planetary reduction gearing for storing energy in said inertia wheel, and means for manually shifting said gear member into meshing engagement with said engine ring gear while said inertia wheel is rotating and thereafter connecting said gear member for drive by said inertia wheel.

14. In an engine starting apparatus of the type in which a ring gear or the like on the engine is engageable during the starting operation by a terminal gear of the starter and such engagement is thereafter interrupted, a gear member adapted to mesh with and drive the engine gear, an inertia wheel, manually operable means including planetary reduction gearing for storing energy in said inertia wheel, and means for manually shifting said gear member into meshing engagement with said engine ring gear while said inertia wheel is rotating and thereafter connecting said gear member for drive by said inertia wheel, said gear member being driven by said inertia wheel through only a portion of said inertia wheel.

15. In an engine starting apparatus of the type in which a ring gear or the like on the engine is engageable during the starting operation by a terminal gear of the starter and such engagement is thereafter interrupted, a gear member adapted to mesh with and drive the engine gear, an inertia wheel, manually operable means including planetary reduction gearing for storing energy in said inertia wheel, and operator controllable means including a connection automatically releasable when the engine is started for effecting engagement of said gear member 70 with said engine ring gear while said inertia

member is rotating and thereafter connecting said gear member for drive by said inertia wheel.

16. In an engine starting apparatus of the type in which a ring gear or the like on the engine is engageable during the starting operation by a terminal gear of the starter and such engagement is thereafter interrupted, a gear member adapted to mesh with and drive the engine ring gear, an inertia wheel, manually operable means including planetary reduction gearing for storing energy in said inertia wheel, and operator controllable means including a connection automatically releasable when the engine is started for effecting engagement of said gear member with said engine ring gear while said inertia member is rotating and thereafter connecting said gear member for drive by said inertia wheel, said gear member being driven by said inertia wheel through only a portion of said planetary gearing.

17. In an engine starting apparatus of the type in which a ring gear or the like on the engine is engageable during the starting operation by a terminal gear of the starter and such engagement is thereafter interrupted, a shaft parallel with the engine crank shaft, a gear member splined to said first shaft and adapted to mesh with and drive the engine ring gear, a parallel shaft, gearing for connecting said first shaft with said parallel shaft, an inertia wheel coaxial with said parallel shaft, manually operable means for storing up energy in said inertia wheel including reduction gearing, elements of which are arranged coaxially with said parallel shaft and operatively connected to said inertia wheel, said parallel shaft being driven by said inertia wheel through a portion of said gearing, and means for manually shifting said gear member relative to said first shaft into meshing engagement with said engine gear while said inertia wheel and parallel shaft are rotating and thereafter connecting said gear member for drive by said inertia wheel through said parallel shaft.

18. In an engine starting apparatus of the type in which a ring gear or the like on the engine is engageable during the starting operation by a terminal gear of the starter and such engagement is thereafter interrupted, a shaft parallel with the engine crank shaft, a gear member splined to said first shaft and adapted to mesh with and drive the engine gear, a parallel shaft, gearing for connecting said first and last mentioned shafts in driving relation, an inertia wheel coaxial with said parallel shaft, manually operable means for storing energy in said inertia wheel including reduction gearing, elements of which are arranged coaxially with said parallel shaft and operatively connected to said inertia wheel, said parallel shaft being driven through a portion of said gearing, and operator controllable means including a connection between said first mentioned gearing and said first shaft automatically releasable when the engine is started for effecting engagement of said gear member with said engine ring gear while said inertia member is rotating and thereafter connecting said gear member for drive by said inertia wheel.

19. In an engine starting apparatus of the type in which a ring gear or the like on the engine is engageable during the starting operation by a terminal gear of the starter and such engagement is thereafter interrupted, a shaft parallel with the engine crank shaft, a gear member splined to said first shaft and adapted to mesh with and drive the engine gear, a parallel shaft, gearing

for connecting said first and last mentioned shafts in driving relation including a gear coaxial with and rotatable relative to said first shaft, a clutch for connecting said last named gear to said first shaft, an inertia wheel coaxial with said parallel shaft, manually operable means for rotating said inertia wheel including a hand crank and planetary gearing connecting said crank with said inertia wheel, said parallel shaft being driven through a portion of said planetary gearing, and means for manually shifting said gear member into meshing engagement with said engine ring gear while said inertia wheel and parallel shaft are rotating, said gear being connected to said first shaft by said clutch only after said gear member is in meshing engagement with said engine ring gear.

20. In an engine starting apparatus of the type in which a ring gear or the like on the engine is engageable during the starting operation by a terminal gear of the starter and such engagement is thereafter interrupted, a shaft parallel with the engine crank shaft, a gear member splined to said first shaft and adapted to mesh with and drive 25 the engine gear, a parallel shaft, gearing for connecting said first and last mentioned shafts in driving relation including a gear coaxial with and rotatable relative to said first shaft, a clutch for connecting said last named gear to said first shaft, an inertia wheel coaxial with said parallel shaft, manually operable means for rotating said inertia wheel including a hand crank and planetary gearing connecting said crank with said inertia wheel, said parallel shaft being driven 30 through a portion of said planetary gearing and means for manually shifting said gear member into meshing engagement with said engine ring gear while said inertia wheel and parallel shaft are rotating, said gear being connected to said first shaft by said clutch only after said gear member is in meshing engagement with said engine ring gear, said clutch for connecting said gear to said first mentioned shaft being automatically releasable to disconnect said gear from 35

said first mentioned shaft when the engine is started.

21. In an engine starting apparatus, the combination of a terminal starting element, a shaft parallel with a line parallel with the shaft of the engine to be started and supporting said terminal starting element, said starting element being reciprocable along its said supporting shaft between positions in engagement with and disengagement from the engine, manually operable 10 inertia means for storing up energy, and means operable at will and including a clutch coaxial with said terminal starting element supporting shaft for connecting said inertia means in driving relation with said terminal starting element supporting shaft. 15

22. In an engine starting apparatus, the combination of a terminal starting element, a shaft parallel with a line parallel with the shaft of the engine to be started and supporting said terminal starting element, said starting element being reciprocable along said terminal starting element supporting shaft between positions of engagement with and disengagement from the engine, inertia means for storing up energy including a 25 driving shaft parallel with said first shaft, gearing for connecting said first shaft to said parallel shaft in driving relation whereby the latter may drive the former, and means operable at will and including a clutch coaxial with said first mentioned parallel shaft for connecting said inertia means through said gearing in driving relation with said first mentioned parallel shaft. 30

23. In an engine starter, the combination of an inertia mechanism, a driving shaft, a gear driven 35 by said inertia mechanism, a gear supported on said driving shaft and engaged by said last mentioned gear, an engine starting element slidably mounted on said driving shaft, sliding clutch means between said first mentioned gear on said 40 shaft and said shaft, and means for sliding said starting element into driving position on said shaft and thereafter connecting said clutch means.

CARL O. NYGREN. 45

CERTIFICATE OF CORRECTION.

Patent No. 2,041,723.

May 26, 1936.

CARL O. NYGREN.

It is hereby certified that error appears in the printed specification of the above numbered patent requiring correction as follows: Page 6, first column, line 35, claim 20, after the word "gearing" insert a comma; and that the said Letters Patent should be read with this correction therein that the same may conform to the record of the case in the Patent Office.

Signed and sealed this 8th day of September, A. D. 1936.

Leslie Frazer

(Seal)

Acting Commissioner of Patents.
